(57) CLAIM

The ornamental design for a card with blister, as shown and described.

DESCRIPTION

FIG. 1 is a front view of the card with blister, showing the new design;
FIG. 2 is a rear view thereof;
FIG. 3 is left-side view thereof;
FIG. 4 is a right-side view thereof;
FIG. 5 is a top view thereof;
FIG. 6 is a bottom view thereof; and,
FIG. 7 is a front and left-side perspective view thereof.

The broken line showing of portions of the card with blister forms no part of the claimed design.

1 Claim, 3 Drawing Sheets
